MAGNETO

Jakob R. Frei, Sidney, N. Y., assignor to Bendix Aviation Corporation, South Bend, Ind., a corporation of Delaware

Application February 12, 1942, Serial No. 430,554

18 Claims. (Cl. 171—209)

This invention relates to ignition apparatus and more particularly to current generating means.

One of the objects of the present invention is to provide a novel magneto generator adapted for use in the ignition system of an internal combustion engine.

Another object of the invention is to provide a magneto generator unit having a novel stator and coil arrangement whereby a more durable and compact structure is obtained, and assembly and construction of the parts of said structure are facilitated.

Another object is to provide a dual magneto with the parts thereof arranged in a novel manner to facilitate inspection, replacement, adjustment and repair of parts while the magneto is mounted on an engine.

A further object is to provide a magneto generator with a novel, oil-tight compartment for containing the transmission means connecting the rotor to the circuit breaker system.

A still further object is to provide a novel compact magneto for energizing a dual ignition system wherein a single rotor means actuates two ignition current generating systems disposed in a novel manner relative to said rotor means.

The above and further objects and novel features of the invention will more fully appear from the following detailed description when the same is read in connection with the accompanying drawings. It is to be expressly understood, however, that the drawings are for the purpose of illustration only and are not intended to define the limits of the invention, reference for this latter purpose being had primarily to the appended claims.

In the drawings, wherein like reference characters refer to like parts throughout the several views,

Fig. 1 is a view partly in side elevation and partly in section, with parts broken away, of one form of magneto embodying the present invention, with a side cover plate thereof removed;

Fig. 2 is a sectional view taken substantially along line 2—2 of Fig. 1;

Fig. 3 is a view in end elevation, with parts broken away, of the said magneto with an end cover plate thereof removed; and,

Fig. 4 is an enlarged sectional view taken substantially along the axis of the circuit breaker cam shaft, said view showing an oil seal for rendering the compartment for the transmission gear oil-tight.

An embodiment of the invention is illustrated

in the drawings, by way of example, in the form of a magneto for energizing a dual ignition system of a multi-cylinder, internal combustion engine. As shown, said magneto comprises a housing or casing including a main central section 10 having a top cover plate 11 (Fig. 2), side cover plates 12, which together with said central section form chambers for containing circuit breaker systems to be later described, and end cover plates 13. A plate 14 is detachably secured to the lower end, as viewed in Fig. 1, of housing section 10 by bolts 15 and constitutes a support for the magneto rotor as well as means for securing the magneto to the engine casing. For the latter purpose, plate 14 is provided with a plurality of recesses 16 adapted to receive bolts (not shown). Suitable thrust bearing means 17, preferably including an oil seal, are carried by said plate to serve as a journal for the lower end of a rotor shaft 18, the latter, as shown, being centrally mounted in housing section 10 with the axis thereof extending vertically. Shaft 18 is adjustably coupled to a driving member (not shown) from the engine by a suitable coupling assembly, for example, of the type shown in U. S. Patent No. 2,266,283, said assembly being secured by nut 19 to the end of said shaft.

Mounted on shaft 18 in the lower part of main casing section 10 is a multiple pole magnetic rotor 20 (Fig. 2) comprising a cylindrical, axially magnetized, permanent magnet 21 and a plurality of laminated, soft iron pole shoes 22 adapted to cooperate in a manner well-known in the art with laminated stator pole pieces 23 (Fig. 1). Since, in the illustrated embodiment, two ignition current generating systems are associated with the single rotor 20, two pairs of laminated stator poles 23 are provided, said pairs being alike in structure and being symmetrically arranged relative to the axis of said rotor. The right-hand set of stator poles is shown in Fig. 1 with one of said poles broken away, and, as shown, each of said poles comprises a vertical portion 23a embedded in or otherwise secured to the wall of casing section 10 adjacent the path of pole shoes 22, said vertical portion having the upper end thereof connected by an elbow 23b to a horizontal portion 23c. The horizontal portions 23c of each pair of stator pole pieces are substantially parallel to each other and extend into end compartments 24 for connection with the core of an ignition coil.

Compartments 24 are formed in both ends of the magneto housing between casing section 10 and removable covers 13, said compartments be-

ing substantially alike in shape and adapted to contain like parts of the two current generating systems. Accordingly, only one of said systems and the parts thereof are described in detail, it being understood that the other system comprises parts similar to those described, said like parts of the two systems being symmetrically mounted relative to the axis of the rotor and being designated by like numerals. Mounted in compartment 24 is an ignition coil 25 (Figs. 1 and 3) comprising the usual primary and secondary windings wound around a laminated metallic core 26 and housed in a casing 27 of insulating material, such as molded "Bakelite." The ends of core 26 are attached in any suitable manner to the ends of portions 23c of stator members 23, thereby completing the magnetic path through the rotor and serving as a support for the coil and its housing 27.

Molded in said coil housing and extending transversely across the entire length of housing 27 is a metallic bar 28 (Figs. 1 and 3) which is electrically connected by means also embedded in the housing structure to the adjacent ends of the primary and secondary windings which it is desired to ground. The projecting ends of bar 28 are secured by bolts 29 (Figs. 1 and 3) to the magneto casing to thus effect a ground connection and afford further support for the coil housing. Also embedded in casing 27 is a metallic rod 30 (Fig. 1) to which the insulated terminal of the primary winding of the coil is connected and which has a terminal screw 31 threaded therein to provide an external terminal for said primary winding. Rod 30 is also connected by a lead 32 molded in casing 27 to a contact 33 mounted in the upper end of said casing, said contact being preferably connected by a plug-in connector 34 to a shielded cable 34' (Fig. 3) supported by and extending through a socket 35 in the side of housing 10. Cable 34' may be connected to ground through an ignition switch (not shown).

Embedded or otherwise secured in the lower end of coil casing 27, with one face thereof exposed, is a metallic plate 36 (Fig. 1) which is connected to the output end of the secondary winding of coil 25. A block or housing 37 of insulating material, such as molded "Bakelite" is rigidly secured to housing section 10 beneath casing 27 by screws 38 and has a condenser molded therein. A metallic rod 39 is slidably mounted in a sleeve 40 carried by said block and is biased into engagement with plate 36 by a spring 41, said rod being electrically connected to one terminal of the condenser in said block. A metallic insert 42 (Fig. 3), carried at the center of a double-ended socket 43 integrally formed with block 37, connects with the other terminal of said condenser and is, in turn, connected through a plug-in connector 44 to a shielded cable 44', said connector and cable being secured to a socket 45 in the side wall of magneto casing 10 and being guided by socket 43. Cable 44' may be connected to a distributor (not shown) of any well-known type, which is preferably mounted in a separate housing, but may be contained in the magneto casing. In order to render the magneto adaptable for ready use with various types of engines, sockets for connectors 34 and 44 are provided in both sides of the magneto casing, the ones not in use being closed by suitable means, such as caps 46.

A condenser block 47 (Fig. 1) is secured to housing section 10 above coil housing 27 by sets of metallic screws 48 and 49, the latter of which

is adapted to connect one terminal of the condenser carried by said block to the magneto housing, thereby grounding said terminal. The other terminal of said condenser is connected by a lead 50 to coil terminal 30, 31, which, as heretofore described, connects with the ungrounded end of the primary winding.

10 Mounted on the left-handed side of condenser block 47, as viewed in Fig. 2, in one of the two symmetrically disposed side chambers or compartments 51 formed by covers 12 and housing section 10 is the circuit primary breaker for the above-described primary circuit, said breaker being actuated by a compensated circuit breaker 15 cam 52. Said cam is mounted on a shaft 53 which is drivably connected, in a novel manner more fully described hereafter, to rotor shaft 18 and is adapted to periodically open a pair of contacts 54 and 55 (Fig. 1), the former of which is connected to lead 50 by a metallic strip 56 and is movable by a cam follower 57. Contact 55 is stationary and is connected to ground through the magneto casing so that said contact points are thus connected in series with the primary winding of the ignition coil 25 and in shunt with the condenser in block 47. Contact points 54 and 55 and cam follower 57 are shown as a single unit 20 adjustably mounted by means of a bracket 58 upon a plate 59 which is, in turn, fixed to casing section 10. Cam 52 is rotated at one-half engine 25 crankshaft speed and is provided with one lobe for each engine cylinder, the spacing of said lobes being such as to compensate for the irregularity of the piston movements in a radial type engine.

30 In order to obtain accurate timing of the opening of contact points 54, 55 with respect to the rotation of rotor 20, cam 52 is coupled to shaft 53 by means of an adjustable coupling, the latter comprising an internally splined sleeve 60 (Fig. 2) drivably engaging the splined end 53a of shaft 53. The inner edge of sleeve 60 is provided with a plurality of ratchet teeth 61 adapted to mesh with an equal number of ratchet teeth 62 on the adjacent face of a ring 63 that is loosely 35 mounted on an external surface of sleeve 60. The other or inner face of ring 63 is provided with a plurality of ratchet teeth 64 numbering one more or less than teeth 61 on sleeve 60 and adapted to mesh with an equal number of ratchet teeth 65 on the adjacent edge of cam 52, the latter being loosely mounted on shaft 53. The coupling assembly 60 and 63 may be releasably held with teeth 61, 62 and teeth 64, 65 in driving engagement by a nut 66 threaded onto shaft 53, so that 40 energy may be transmitted from shaft 53 through sleeve 60 and ring 63 to cam 52.

45 When it is desired to make an angular adjustment of cam 52 relative to shaft 53, nut 66 is loosened sufficiently so that the ratchet teeth on sleeve 60 or cam 52 can pass over the corresponding teeth on ring 63. By now angularly moving the shaft first in one direction an amount equal to the pitch of teeth 62 and then in the opposite direction an amount equal to the pitch of teeth 64, or vice versa, angular adjustments equal to the difference in the pitch of said teeth can be effected.

50 To drivably connect cam shaft 53 to rotor shaft 18, a bevel gear 67, keyed or otherwise secured to said cam shaft intermediate the ends thereof, meshes with a second bevel gear 68 splined to the upper end of said rotor shaft. Novel means 55 are provided for mounting said shafts so as to form an oil-tight compartment 69 for gear drive 67, 68 sealed from chambers 24 and 51 and from

the portion of section 10 containing rotor 20. Bearing and sealing means 70, which journal the upper end of the rotor shaft, are disposed between rotor 20 and gear 68 in fluid-tight engagement with the wall of housing section 10. Said bearing and sealing means are shown in outside view, the same having incorporated therein the same elements hereinafter described in connection with the mounting of opposite ends of cam shaft 53.

As shown in Figs. 2 and 4, cam shaft 53 is supported in casing 10 at two points between chamber 69 and chambers 51 by means of ball bearings 72 which are fitted into said casing. A novel combination of oil sealing means is provided in the vicinity of each bearing 72 for preventing leakage of oil from compartment 69 during operation of the magneto, said means comprising a novel oil seal 71.

Sealing means 71, as illustrated (Fig. 4), comprise an outer cylindrical member or housing 13 having a press fit in a central opening in plate 59 through which shaft 53 passes. An inwardly extending radial flange 74 is formed on member 73 at the end thereof adjacent chamber 69 and has an inner cylindrical portion or member 75 attached thereto, the latter member being disposed a short radial distance from said shaft. Secured by a force fit in portion 75 to have sliding engagement with said shaft is a member 76 having an external shoulder 77 pressed against flange 74. The section of shaft 53 engaged by member 76 is preferably provided with a reverse thread 78 which, during rotation of the shaft, tends to drive any oil trapped between said shaft and said member back in the direction of compartment 69. To trap the oil which escapes into housing 13 and prevent the flow thereof from said housing along shaft 53 into chamber 51, particularly when shaft 53 is not rotating, a cylindrical member 79 having a ring 80 of carbon secured in a fluid-tight manner in the end thereof remote from compartment 69 surrounds said shaft. Ring 80 is adapted to engage an abutment or shoulder rotatable with said shaft, such as the inner end of cam 52, and is pressed into fluid-tight contact with said abutment by a plurality of springs 81 contained in housing 13. As shown, springs 81 are spaced about the periphery of the shaft and one end thereof bears against flange 74 while the other end presses against a flange member 82 rigidly secured to member 79. An inwardly extending flange member 83 is secured in the end of housing 13 and acts to prevent springs 81 from ejecting cylindrical member 79 from the oil seal assembly when cam 52 or said assembly is removed from shaft 53. To seal the annular space between member 79 and flange member 83, an annular sheet of flexible, oil-proof and oil-resistant material 84 is suitably secured across said space by being clamped between flange member 82 and member 79 at its inner edge and between flange member 83 and housing 13 at its outer edge. A sealing action is thus obtained at both ends of sealing means 71, insuring fluid-tightness.

As a further precaution against the escape of oil from chamber 69 along shaft 53, a pair of oil slingers 90, 91 may be mounted on said shaft for rotation therewith, said slingers being preferably located adjacent the inner ends of bearings 72 so as to sling oil back into said chamber. As shown in Fig. 4, slinger 90 is clamped between a shoulder 82 formed on shaft 53 and the inner race of left-hand bearing 72, while slinger 91 is

similarly held between the hub of gear 67 and right-hand bearing 72. A third oil slinger (not shown) may be mounted on the upper end of rotor shaft 18 as a part of assembly 70.

Means are provided for ventilating the interior of the magneto housing and, as shown, comprise passages 93 (Fig. 2) connecting each of chambers 51 with the portion of the interior of housing section 10 which contains rotor 20. Ventilating members 94 are provided for each of compartments 51 and 24, preferably by being connected to covers 12 and 13 for said compartments. Each of said ventilating members admits air into the housing and is preferably provided with a suitable means, such as a baffle arrangement for preventing water and foreign matter from entering the housing.

There is thus provided a novel dual ignition magneto unit comprising a single rotor and two like current generating systems energized thereby, said unit including a novel oil-tight compartment for the transmission gearing between said rotor and the circuit breaker drive shaft. The like parts of said current generating systems are arranged in a novel manner relative to the rotor, the same being symmetrically disposed in relation to the axis of the rotor to provide a compact structure which can be readily constructed, assembled, inspected and repaired. Novel means are also provided for making the necessary electrical connections between the ignition coil, condenser, circuit breaker, distributor, ground and ignition switch whereby the length and number of wires within the magneto housing are greatly reduced, thereby minimizing the probability of failure in the ignition system due to chafing or breaking of wires. Additionally, novel means are provided for adjustably connecting a circuit breaker cam to the driving shaft therefor.

Although only a single embodiment of the invention has been illustrated and described, it is to be expressly understood that many changes, including rearrangements and design of the parts illustrated, which will now be apparent to those skilled in the art, may be made without departing from the spirit and scope of the invention. For a definition of the limits of the invention, reference is had primarily to the appended claims.

What is claimed is:

1. In a magneto having a single magnetic rotor and a pair of current generating systems energized by said rotor, each of said systems comprising an ignition coil, condensers connected to the windings of said coil, and a circuit breaker, means for housing and mounting the above elements of said systems whereby like parts of the latter are symmetrically disposed relative to the axis of rotation of said rotor, said means comprising side compartments for the circuit breakers disposed on opposite sides of a plane containing said axis and compartments for the coils and the condensers connected thereto, said last-named compartments being disposed on opposite sides of a plane containing said axis and perpendicular to said first-named plane.

2. In a magneto having a single rotor and a pair of current generating systems energized by said rotor, each of said systems comprising stator poles, an ignition coil, condensers connected to the high potential ends of the windings of said coils and a circuit breaker, means for housing and mounting the above elements whereby the like parts of said systems are symmetrically disposed relative to the axis of rotation of said rotor, said means comprising a central compartment for

said rotor, compartments for the circuit breakers disposed on opposite sides of said axis and a plane containing the latter, and compartments disposed on opposite sides of a plane containing said axis and perpendicular to said first-named plane for the coils and the condensers connected thereto, said stator poles being mounted in said housing and extending into said last-named compartments.

3. In a magneto having a rotor and a pair of current generating systems energized by said rotor, each of said systems comprising an ignition coil and a circuit breaker, means for housing and mounting the above elements whereby like parts of said systems are symmetrically disposed relative to the axis of rotation of said rotor, said means comprising a central chamber for said rotor, side compartments for the circuit breakers disposed on opposite sides of said axis and a plane containing the latter and compartments for said ignition coils disposed on opposite sides of said axis and a plane containing said axis and perpendicular to said first-named plane, each of said compartments being provided with a removable cover.

4. In a magneto having a rotor, a pair of current generating systems energized by said rotor, each of said systems comprising an ignition coil and a circuit breaker, drive means operatively connecting the operating means for said circuit breakers to said rotor, and means for housing the foregoing elements comprising a central chamber for said rotor, a side compartment for each of said circuit breakers, a compartment for each of said ignition coils, and a substantially liquid-tight compartment disposed between said side compartments for containing said drive means, each of said compartments having a removable cover.

5. In a magneto having a rotor, a pair of current generating systems energized by said rotor, each of said systems comprising an ignition coil and a circuit breaker, drive means operatively connecting the operating means for said circuit breakers to said rotor, and means for mounting and housing the like parts of said systems whereby said parts are symmetrically disposed relative to the rotor axis with the coils and circuit breakers on different sides of said axis, said last-named means including a central compartment for said rotor, a side compartment for each of said circuit breakers, and a substantially liquid-tight compartment disposed between said side compartments and above said central compartment for containing said drive means.

6. In a magneto having a dual current generating system, a single rotor, a pair of circuit breakers, a housing having a central compartment for said rotor and a side compartment for each of said circuit breakers, a common drive shaft with operating means thereon for said circuit breakers, power transmitting means connecting said drive shaft to said rotor, and a substantially liquid-tight chamber disposed between said side compartments and adjacent one end of said central compartment for containing said transmitting means.

7. A magneto having a dual current generating system, a housing, a magnetic rotor mounted therein, a shaft rotatably mounted in said housing, means for drivably connecting said rotor and shaft, a substantially liquid-tight chamber containing said connecting means, one end of the shaft of said motor extending into said chamber and said first-named shaft extending through

and having both ends thereof projecting out of said chamber, and a pair of circuit breaker cams mounted on said first-named shaft at opposite ends thereof.

5 8. In a magneto having a rotor and an ignition coil, a central casing for mounting the rotor, a chamber for containing the ignition coil, a pair of laminated stator poles, each of said poles having one end portion thereof mounted in said casing to be adjacent said rotor and with the laminations thereof extending longitudinally in a direction parallel to the rotor axis and the other end portion having the laminations thereof extending longitudinally substantially perpendicularly from said first-named end portion into said chamber to connect with one end of the core of said ignition coil.

9. In a magneto having a rotor and an ignition coil, a pair of stator poles, each of said poles 20 having an end portion thereof mounted adjacent said rotor and extending longitudinally in a direction parallel to the rotor axis and the other end portion extending longitudinally substantially perpendicularly from the first-named end portion to connect with one end of the core of said ignition coil.

10. In a magneto having a housing, an ignition coil comprising primary and secondary windings, an insulating casing for said coil, common means for supporting said casing and grounding one end of each of said windings, a metallic strip molded in the upper end of said casing and connecting with the ungrounded end of the primary winding, an exposed terminal partially embedded in the upper end of said casing and connecting with said strip, a socket in said housing for supporting an ignition switch cable for contact with said terminal, a second terminal embedded in the upper end of said casing and connecting with said strip, a condenser supported by said housing above and adjacent to said casing, means for connecting said condenser to said second terminal, a metallic contact embedded in the lower end of said casing and connecting with the ungrounded end of said secondary winding, a condenser block secured to said housing and disposed below said casing, and means slidably connecting the condenser in said block to said metallic contact.

11. In a magneto having a metallic housing, an ignition coil comprising primary and secondary windings, an insulating casing for said coil, a metallic member molded in said casing and connected to one end of each of said windings, 55 said member being secured to said housing to support said coil and ground said windings, a metallic strip completely embedded in said casing and connecting with the ungrounded end of said primary winding, a pair of terminals connected to said strip, socket means in said housing adapted to hold an ignition switch cable in contact with one of said terminals, a condenser, a circuit breaker, and means connecting said condenser and circuit breaker to the other of said terminals.

12. In a magneto, a housing, an ignition coil comprising primary and secondary windings, an insulating casing for said coil, common means for supporting said coil and grounding one end of the primary winding thereof, a metallic strip embedded in said casing and connecting with the ungrounded end of the primary winding, an exposed terminal embedded in said casing and connecting with said strip, a socket in said housing for supporting a cable for contact with said ter-

minal, a second terminal embedded in said casing and connecting with said strip, a condenser supported by said housing adjacent said terminals, and means for connecting said condenser to said second terminal.

13. In a magneto, an ignition coil comprising primary and secondary windings, an insulating casing for said coil, means for grounding one end of said secondary winding, a metallic plate embedded in said casing with one face thereof exposed, said plate being connected to the ungrounded end of said secondary winding, and a condenser block mounted adjacent said casing, said block housing a condenser, a spring-pressed contact connected to one terminal of said condenser, said contact being biased into engagement with said plate, and a metallic member connected to the other terminal of said condenser, a socket being formed in said block for receiving a cable adapted to connect with said metallic member.

14. In apparatus of the class described, a rotatable shaft, a circuit breaker cam loosely mounted on said shaft and surrounding a reduced portion thereof, a sleeve drivably connected to said reduced portion, a ring loosely mounted on said sleeve within said cam, said ring having unequal numbers of ratchet teeth on opposite faces thereof cooperating with ratchet teeth on said sleeve and cam, and means threaded onto said shaft for holding said ratchet teeth in driving engagement, whereby said cam is drivably connected to said shaft for angular adjustment relative thereto.

15. A magneto comprising housing means, a magnetic rotor rotatably mounted in a central portion of said housing means, the latter having a plurality of removable covers forming four compartments spaced at 90 degree intervals around the axis of rotation of said rotor, an ignition coil in each of two oppositely disposed compartments having the cores thereof extending at right angles to a plane containing said axis, stator means for operatively magnetically connecting said cores and said rotor, a condenser mounted at one side of each of said coils and connected to the secondary winding thereof, said condensers being mounted in corresponding parts of said last-mentioned compartments, a condenser mounted at the other side of each of said

coils and connected to the primary winding thereof, said last named condensers being mounted in corresponding parts of said last named compartments, circuit breaker means in 5 each of the other oppositely disposed compartments, means connecting each of said circuit breaker means to one of said last named condensers and one of said coils, cam means on opposite ends of a shaft extending at right angles 10 to said axis for actuating said circuit breaker means, and means in a substantially liquid-tight compartment of said housing means for drivably connecting said shaft and rotor.

16. In a magneto, a magnetic flux conducting 15 rotor, a coil with a metallic core having the longitudinal axis thereof in a plane perpendicular to the axis of rotation of said rotor, and a pair of laminated stator poles, each comprising a plurality of elongated metallic straps, one end of each of said poles being adjacent said rotor and having the laminations thereof extending longitudinally in a direction parallel to said rotor axis and the other end of each pole being operatively connected with said core and having the laminations thereof extending longitudinally in 20 a direction parallel to said plane.

17. In a magneto, a magnetic flux conducting 25 rotor, a coil having a metallic core mounted at one side of said rotor, and means for magnetically connecting said rotor and core comprising a pair of laminated stator poles each having a bend therein dividing the same into two end portions extending at substantially right angles to each other, one end portion of each pole being adjacent said rotor with the laminations thereof extending longitudinally in a direction parallel to the axis of rotation of said rotor.

18. In apparatus of the class described, a rotatable shaft, an element such as a circuit breaker 30 cam loosely mounted on said shaft, a sleeve drivably connected to said shaft, a ring loosely mounted on said sleeve, said ring having unequal numbers of ratchet teeth on opposite faces thereof cooperating with like numbers of ratchet 35 teeth on said sleeve and element, and means threaded onto said shaft for holding said ratchet teeth in driving engagement, whereby said element is drivably connected to said shaft for angular adjustment relative thereto.

JAKOB R. FREI.
